DOOR OPENING MECHANISM

Matt A. Volf, Cleveland, Ohio

Application August 1, 1956, Serial No. 601,516

4 Claims. (Cl. 268—59)

This invention pertains to a door opening device for garage doors and the like which are mounted to move upwardly and downwardly on tracks.

An object of the invention is to provide a motorized garage door opening device which is carried by the door and acts on the tracks holding the door.

Another object of the invention is to provide a garage door opening device which is easily and quickly installed in any garage where the doors slide on tracks, it being unnecessary to install special tracks or cables for the opening device to operate on.

Still another object of the invention is to provide an operating device for a door which slides vertically on a track, the device being easily mounted between the door and the already existing track thereby obviating an expensive and time-consuming installation.

Another object of the invention is to provide an electric circuit for a garage door actuating device which automatically, as the door reaches each of its terminal positions, throws the circuit into proper condition for its next motion.

A further object of the invention is to provide a safe, inexpensive garage door actuating mechanism, the motion of which can be stopped immediately in an emergency.

For a better understanding of the present invention together with other and further objects thereof, reference is had to the following description taken in connection with the accompanying drawings and its scope will be pointed out in the appended claims.

An aspect of the present invention is the provision of a motor device for opening and closing a garage door or the like, wherein the motor means is connected to the door and includes a driven roller in frictional driving engagement with the track.

Figure 1 of the drawing is a view showing the motor device of the invention installed to open and close a typical garage door.

Figure 2 is a side view, partially broken away, showing the motor device and its mounting to a door and to a track.

Figure 3 is an end view of the motor device of the invention.

Figure 4 is a side view showing a manually operable release mechanism, and

Figure 5 is a circuit diagram showing the electrical circuit for the motor device.

With reference to Figure 1, there is shown a typical vertical lift type garage door 10, mounted on a pair (only one shown) of spaced apart rails 11. In a typical garage door installation the rails upon which the door is mounted for upward and downward movement are suitable for the installation of the device of the invention. Preferably, as shown in Figure 3, the rail 11 has a C-shaped cross-section, though if it does not the device herein described will still operate.

An electric motor device is provided, encased in a housing 12, which drives a worm gear 13 and through the worm gear a gear 14 which in turn is connected to a

2

large rubber wheel 15. One end of the housing 12 is secured to the door 10 by means of a plate 16 which is bolted to the door by bolts 17, and a hinge device 18 is included in the mounting device. The hinge which is illustrated in Figure 2 comprises a pair of spaced plates 19 connected to a plate 16 and between which an axle 20 is mounted. A U-shaped connector 21 is mounted around the axle 20 and is connected by nuts 22 to the mounting arm 23. The other end of the mounting arm 23 is secured to the housing 12 of the motor by bolts 24. A wheel 25 is connected to the axle 20 and positioned within the C-shaped track 11 to guide and stabilize the unit as it moves up and down as the door is operated. Relative rotary motion can take place between the U-shaped connector and the axle 20, thereby establishing a pivoting action at the location where the arm 23 connects to the door 10. The wheel 25 and axle preferably are part of the regular equipment which supports the door in the tracks 11.

The peripheral edge of the rubber tire 15 of the drive wheel preferably is shaped to conform to the shape of the bottom of the track 11. Thus if the bottom edge of the track is convex, the surface of the wheel 15 should be concave, as shown in Figure 3, to better grip the track. A pinch roller 27 is mounted on the housing 12 at a location adjacent the drive wheel 15, so that the track 11 may be pinched between the two wheels when the unit is installed. It is desirable, though not essential, that the pinch roller 27 have a resilient, rubber surface for better coupling to the track 11. The pinch roller 27 is connected by axle 28 to a horizontally extending, pivotably mounted, cross-bar 29 which is secured to the motor housing 12 by means of a nut device 30 which permits a slight rocking motion of the bar 29 to decouple the wheel 27 from the track 11.

As shown in Figure 3 the cross-bar 29 is mounted in a channel 45 in the upper part of the motor housing 12, and the bottom 46 of the channel is curved lengthwise to facilitate a slight rocking motion of the cross-bar 29.

The opposite end 31 of the bar 29 is in engagement with one leg 32 of a crank member 33 which is pivotably secured to the motor housing 12 by bolt 34. A chain 36 is connected to the other leg 35 of the crank 33 so that a downward pull on the chain 36 causes the crank leg 32 to slip out from underneath the end 31 of the cross-bar 29, thereby decoupling the wheel 27 from the track 11 and reducing the "pinch" on the track by the two wheels 15, 27. The nut device 30 has a stem which extends through a bore in the bar 29, the size of the bore being larger than the size of the bolt to provide a slight amount of clearance so that the bar 29 can rock slightly with respect to the motor housing 12.

The other end of the chain 36 is connected to a crank member 50 mounted on the inside of the door 10, the crank member 50 forming part of a lock device 51 which extends through the door 10 to the outside. If the electric power to the motor driving the door opener should fail, the operator merely unlocks the lock device 51 from the outside and turns the crank member 50, thereby pulling chain 36 which releases the tight frictional coupling of the motor on the track 11. With this coupling released the operator can easily open the door by hand. When electric power is restored, he can easily re-engage the electric power drive by merely pushing the end 35 of the crank 33 upward until the end 32 of the crank is in position underneath the end 31 of the cross bar 29, thereby pivoting the bar 29 slightly on the curved surface 46 and around bolt 30 as a pivot, to tightly re-engage the wheel 27 on the inside surface of the curved track 11.

The electric motor within the housing 12 is of the reversible type, and a switch actuating device 60 is mounted by bolt 61 of the motor housing 12. A long electric

cable 62 is connected from an energy source, not shown, to the motor. At each end of the transverse of the door 10 there is a switch actuating member 65 (only one shown) which throws the motor switch, putting it in condition for motion in the proper direction when the operator next signals the door to open. Such a signal may be by radio, push button, super-sonic device, or other such mechanism known to the art.

Figure 5 illustrates the electric circuit for the door opening device.

The electric motor 70 has windings 71, and the direction of rotation of the motor 70 depends upon the direction of current flow through the windings. One or more switch stations 72, 73 are provided, for example switch station 72 may be within the house and station 73 may be a manually operated switch mounted on a post beside the driveway, or it may be a radio or supersonically actuated switch. Switches 72 and 73 normally are in a neutral position illustrated by switch blade 72', and are electrically connected in parallel so that actuation of either one will open or close the door 10, depending upon whether the starting position of the door is closed or open. For example, if the door is closed, the next actuation of either switch 72, 73 will cause the door to open; but if the door is in its open condition the next actuation of either switch will cause the door to close. Thus the electrical wiring for the door operator of this invention is quite simple. The electrical equipment within the dash-dot square is mounted within the garage where it is protected from the weather, and switches 72 and 73 may also be protected. Thus, the only outside wires 75 are those running from the house to the garage, in the event there is a control switch 72 or 73 inside the house.

Electric power is supplied across wires 80, 81, and with switch blade 73' in its downward position to close the door an electric circuit is made in one direction by the dotted line connections 82, 83 and 84, through the motor 70 and its windings 71, thereby driving the motor in the door closing direction. The reversing switch mechanism is shown inside the dotted line box 60' and includes the switch wand 60. It is mounted on and travels with the motor 70, windings 71 etc. When the door 10 reaches its "closed" position the extended wand 60 (Figure 2) throws switch 60' into the condition shown by the dashed connections 85, 86, 87, instead of that shown by the dotted connections 82, 83, 84. This breaks the circuit which was originated by closing switch 73' to its downward position, and the entire circuit is de-energized. Further downward closing of any or all of the actuating switches 72, 73 is inoperative since the door is closed.

When the operator wants the door to open, any one of the operating switches 72, 73 is thrown to its upward position, thereby making a circuit through the dash line connections 85, 86, 87 to apply power to the motor 70 and windings 71 in the opposite direction, causing the door to open, and upon reaching its "open" position to cause wand 60 to throw switch 60' back to its previous condition where the next proper actuation of an operating switch 72, 73 will cause the door to close.

It will be seen that the device of this invention is easily mounted on already existing vertically operable garage doors simply by connecting the motor unit to

the door and placing the two rollers on opposite sides of the already existing track. Installation of the limit devices 65 for throwing the switch completes the installation. If desired, the bias releasing device may be connected through the door for convenience in the event of a power failure. The unit is very safe since it is a frictional drive from motor to track, and if anything such as a child's bicycle is underneath the door as the door closes it will not crush the bike, but will slip between the drive wheel and the track. Further, with the bias release chain 36 installed, a pull on the chain will quickly release the driving power to stop the door.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A door opening device for use with a vertically sliding door mounted on track means, comprising, in combination, reversible electric motor assembly means, means for connecting said motor assembly means to said door, a pair of pinch rollers at least one of which is made of resilient rubber-like material connected to and forming a portion of said motor assembly means and at least one of which is driven by the motor, one of said pair of pinch rollers engaging one side of said track means and the second of said pinch rollers engaging the opposite side of said track means at a location opposite said first pinch roller for frictionally driving said door, the motor and said pinch rollers moving as a unit with said door as said door is opened and closed, pinching means connected to and forming a portion of said motor assembly means for limiting the distance apart of said rollers on opposite sides of said track means, and electric circuit means including switching means connected to said reversible electric motor.

2. A door opening device as set forth in claim 1, further characterized by said means for connecting said motor assembly means to said door comprising a plate secured to said door, said plate including a portion of a hinge, complementary hinge means forming a portion of said motor assembly means cooperating with said plate hinge portion to pivotably secure said motor assembly means to said door whereby said motor assembly means can freely pivot with respect to said door.

3. A door opening device as set forth in claim 1, further characterized by said pinching means including spring bias means for urging said pinch rollers together when they are on opposite sides of said track means.

4. A door opening device as set forth in claim 3, further characterized by said pinching means including release means whereby said spring bias may be released.
